(57) **CLAIM**

The ornamental design for a headlight lens module, as shown and described.

DESCRIPTION

FIG. 1 is a front view of a headlight lens module;

FIG. 2 is a rear view thereof;

FIG. 3 is a left-side view thereof;

FIG. 4 is a right-side view thereof;

FIG. 5 is a top view thereof;

FIG. 6 is a bottom view thereof; and,

FIG. 7 is a perspective view thereof.

The broken lines illustrate features of the headlight lens module that form no part of the claimed design.
